UNITED STATES PATENT OFFICE

2,220,279

HANDSET TELEPHONE

Alexander C. Reid, Genoa, Ill., assignor to Leich
Electric Co., Genoa, Ill., a corporation of Illi-
nois

Application September 20, 1937, Serial No. 164,752

3 Claims. (Cl. 179—100)

The present invention relates to telephones and more particularly to improvements in handset telephones and ringers to be used therewith whereby to provide a simplified and flexible telephone apparatus which is readily adapted to the many problems of mounting and support that are encountered in the installations of this type of apparatus.

My invention contemplates the provision of a handset telephone so constructed that the talking unit, the handset unit, and the ringing unit are complete in and of themselves, but are so arranged as to readily fit together to provide a complete self contained portable telephone.

The specific features of novelty and arrangement will appear more fully in the following description, reference being had to the accompanying drawings wherein a preferred form of the invention is shown. It is to be understood, however, that the drawings and description are illustrative only and are not to be taken as limiting the invention except in so far as it is limited by the claims.

In the drawings—

Fig. 1 is a view in perspective of the complete handset telephone;

Fig. 2 is a transverse sectional view taken centrally through the telephone;

Fig. 3 is a sectional view taken on the line 3—3 of Fig. 2 with the handset broken away;

Fig. 4 is a sectional view looking up on the line 4—4 of Fig. 3;

Fig. 5 is a sectional view looking down on the line 5—5 of Fig. 8;

Fig. 6 is a view in perspective of the telephone showing the handset and talking unit combined, but with the ringing unit removed;

Fig. 7 is an end view of the device shown in Fig. 6 with the handset removed and with certain parts broken away to show the interior construction;

Fig. 8 is a sectional view taken substantially on the line 8—8 of Fig. 5;

Fig. 9 is a wiring diagram illustrating the circuit connections for the talking and ringing circuits where the ringing is entirely over a metallic circuit; and

Fig. 10 is a similar view showing the arrangement when the ringing circuit is through a condenser of the ringing unit to ground.

Referring now in detail to the drawings, for the sake of simplicity in description, we will refer to the several parts of the apparatus by the usual terms employed to identify them in this art as comprising a handset 10, a talking unit in a casing 11, and a ringing unit 12. The handset comprises the usual transmitter 13 and receiver 14 connected by a hollow hand piece 15 in the usual fashion. The casing parts of the handset are preferably made by molding

them of a suitable plastic compound such as the synthetic resin compound sold under the trade name of "Bakelite."

The talking unit 11 comprises a casing having an open rectangular bottom end 17 recessed around its periphery at 18 for a purpose which will presently appear. The casing 11 is gradually reduced in cross section upwardly from all four sides so as to provide a front side 19 which slopes upwardly and is provided with a large aperture 20 which may be utilized for mounting a dial or which may be closed by means of a metal number plate 21. The flange 22 is provided around a portion of the periphery of the opening 20, and suitable screws 23 are used to clamp the metal plate 21 in place. The screws 23 screw into a complementary plate 24 that is fixed directly to the plate 21. The back wall 25 of the casing 11 is provided with an aperture 26 through which connecting leads may enter the interior of 20 the casing.

The casing 11 is open at the top as indicated at 27. A combined cradle and hook switch unit 28 is seated upon and covers the open top of the casing 11. The cradle and hook switch unit 28 is secured to the casing 11 by a pair of screws 29 and 30 that are threaded into a pair of lugs 31 and 32 formed on the inner wall of the casing 11. A central pin 33 is mounted in the unit 28 and is normally pressed upwardly by a spring 34 seated in an aperture 35 that is cut in the molded body of the unit 28. The pin 33 has an enlarged head against which the spring bears, and the spring is supported by a bearing plate 36 set in the body of the unit 28. The hook switch comprises two stationary contact members 37 and 38 and two spring contact members 39 and 40 cooperating therewith, the contact members being mounted upon a depending lug 41 of the unit 28. A U-shaped bracket 42 is fastened to the body of the unit 28 at the end opposite the lug 41. This bracket mounts an actuating lever 43 by means of a pin 44. The lever 43 has a pair of posts 45 and 46 thereon which posts are constructed of a suitable insulating material and are adapted to engage the spring contacts 39 and 40 and press them outwardly against the stationary contacts 37 and 38. The free end of the lever 43 has a portion 47 adapted to be engaged by the pin 33 and 50 pressed downwardly to separate the spring contacts 39 and 40 from their stationary contacts 37 and 38.

Within the casing 11 an induction coil 48 is mounted upon a laminated core 49. The entire 55 coil and core are secured to a pair of bosses 56 and 51 formed on the inner wall of the casing 11. The particular mounting of the induction coil is accomplished by extending the core 49 beyond the coil 48 at both ends. A pair of links 60

52 and 53 are secured to the core 49 by screws and are mounted on bosses 50 and 51 by screws. The induction coil unit has end plates 54 and 55 of insulating material at the opposite ends of 5 the coil 48, and the wiring terminals for the coil 48 are brought out through the plates 54 and 55 as indicated at 56 and 57. On the back wall 16 of the casing 11, a shoulder is provided at 58 (see Fig. 2) upon which a terminal strip 59 is mounted by means of suitable screws. The 10 terminal strip 59 has a series of wiring terminals indicated by the numeral 60 by which the necessary connection may be made for the circuits of the telephone. Adjacent the front of the casing 15 11 and beneath the sloping portion 19 thereof, bosses 61 and 62 are provided, and a condenser 63 is mounted between the bosses 61 and 62. Suitable brackets 64 and 65 are secured to the 20 bosses 61 and 62 by means of screws. The casing 11 is also formed with ribs 66 and 67 against which the opposite ends of the condenser 63 are held by the brackets 64 and 65. The casing 11 is provided with a pair of mounting lugs 68 and 69 which are arranged at the opposite ends of the 25 casing 11 and are provided with screw threaded openings indicated at 70 and 71 in Fig. 3.

Thus the casing 11 and the parts mounted therein comprise a complete talking unit when assembled with the cradle and hook switch unit 30 28 and the handset 10. If only a talking unit is desired, a base plate 72 (see Fig. 7) having a suitable felt cover 73 may be mounted to close the bottom opening of the casing 11, as shown in Fig. 7, by means of suitable screws, one of which is 35 indicated at 74 in Fig. 7. The complete talking unit formed in this fashion is illustrated in perspective in Fig. 6.

The casing 11 is adapted to cooperate with the 40 ringing unit 12 to provide a complete portable telephone. In this case, the talking unit is mounted upon the ringing unit as shown in Figs. 1 to 4 inclusive.

The ringing unit is made up by taking the base 45 plate 72 with its felt covering 73 and an annular molded side wall 75 which seats within the base plate 72 in the same manner as the lower edge of the casing 11 seats therein. To connect the parts together, a pair of posts 76 and 77 having screw threaded projections thereon are threaded 50 into the openings 70 and 71 provided in the lugs 68 and 69. These posts 76 and 77 have screw threaded openings therein at their lower ends to receive a pair of screws 78 and 79 by which the base plate 72 can be clamped to the post and thus 55 clamp the annular member 75 in the position shown in Fig. 3. At its opposite ends, the annular member 75 has a series of openings indicated at 80 and 81. Similar openings are provided in the back wall of the member 75 at 82 and 83 (see 60 Fig. 5).

The base plate 72 has mounted thereon a complete ringing unit which comprises bells 84 and 85 fastened to the base plate 72 by screws 86 and 87. An arm 88 is carried by a pivoted armature 89 that is pivoted on a frame 90. The frame 90 cooperates with a second frame 91 to support ringing coils 92 and 93 and a core piece 94. The frame 91 is secured to the base plate by screws 91a and 91b. The base plate also has mounted 70 thereon a condenser 95 and a terminal block 96, the terminal block being mounted upon posts 97 which are fixed to the base plate in a suitable manner.

When it is desired to utilize the ringing unit 5 separate from the talking unit, as for example mounting it upon a wall, the posts 76 and 77 are inverted as shown in Fig. 8 so that their screw threaded ends thread into a pair of openings 98 and 99 which are provided in the base plate 72 and which are normally used for receiving the screws 78 and 79. A cover plate 100 is then 10 mounted upon the posts 76 and 77 by means of screws 101 and 102.

The wiring diagram of the apparatus when connected for ringing on a metallic circuit is illustrated in Fig. 9. All of the connections are made through the terminal strip 59 so as to connect the transmitter 13, the receiver 14, and the 15 ringing unit 12 in circuit with the coil 48 and the condenser 63, the hook switch unit 28 being also connected through the terminals 60 on the terminal strip 59 as will be readily understood. The casing 11 carries all of the talking circuit connections. The hook switch mechanism is all carried by the unit 28, and the ringing mechanism is all carried by the unit 12. When it is desired to utilize the condenser 95 in the ringing unit for connection in the ringing circuit so as to ring to 20 ground, these circuit connections are as shown in Fig. 10.

From the above description, it is believed to be 25 evident that I have provided a very compact and flexible structure by which the several parts of the telephone may be assembled to provide a complete portable telephone unit including the ringing unit and in which the talking unit of the telephone may be readily used separately from the ringing unit. The particular shape of the casing 30 for the ringing unit, as shown herein, may be varied to adapt the telephone for mounting upon walls or any other suitable position within the scope of the present invention. Obviously, also 35 the particular details of circuit are not important 40 in the present combination.

Having thus described my invention, what I 45 claim as new and desire to secure by Letters Patent is:

1. A telephone set comprising in combination, 45 a telephone comprising a casing open at top and bottom, a cradle closing the top of said casing, a hook switch mounted entirely on said cradle, a talking circuit mounted in the casing, and a ringing unit comprising a shallow open topped casing, 50 a ringer mounted therein, and means for seating and securing said first named casing upon the last named casing.

2. A handset telephone comprising a talking unit, an open bottomed casing therefor, a ringing 55 unit, an open topped casing therefor, said casings having matching peripheral edges adapted to engage each other to complete an enclosure for the talking and ringing units, said first named casing having a top opening, and a combined handset 60 support and hook switch unit closing said opening.

3. In a telephone set, a base plate, a ringer mounted thereon, and a separate annular side wall member surrounding said ringer and resting 65 on said base plate, a closure, and means connecting the closure and base plate and adapted to clamp said member between the base plate and the closure whereby to secure it in place.
